UNITED STATES PATENT OFFICE.

JACOB B. BLOW, OF PITTSBURG, PENNSYLVANIA, ASSIGNOR TO BLOW
COLLAPSIBLE STEEL CENTERING COMPANY, OF PITTSBURG, PENNSYLVANIA, A CORPORATION OF NEW JERSEY.

MOLD AND CENTERING DEVICE FOR SEWERS, CONDUITS, &c.

No. 851,895.

Specification of Letters Patent.

Patented April 23, 1907.

Application filed January 20, 1906. Serial No. 296,939.

To all whom it may concern:

Be it known that I, JACOB B. BLOW, a citizen of the United States, residing at Pittsburgh, in the county of Allegheny, State of Pennsylvania, have invented a new and useful Mold and Centering Device for Sewers, Conduits, &c., of which the following is a specification.

My invention consists of a device for molding and centering sewers, conduits, manholes, stacks, pipes and the like that may be formed of concrete, cement or other plastic material, the construction of the same being hereinafter described and the novel features pointed out in the claims.

Figure 1 represents a diametrical section of a mold and centering device embodying my invention.

Figure 2 represents a longitudinal section thereof on line $x-x$ Figure 1.

Figure 3 represents a section of a portion on line $z-z$ Figure 2 on an enlarged scale.

Figure 4 represents a section of a portion on line $y-y$ Figure 3.

Figure 5 represents an end view of another portion of the device embodying my invention.

Figure 6 represents a longitudinal section thereof.

Similar letters of reference indicate corresponding parts in the figures.

Referring to the drawings:

A and B designate the upper and lower interior sections of a mold or centering device, and C designates an upper exterior section thereof.

Connected with the interior of the upper section are brackets D and connected with the interior of the lower section are brackets E, said brackets being preferably of angular form.

To the upper limbs or ends of the brackets D there are connected the screw-threaded rods F, with whose inner ends engage the threaded buckle G.

To the upper limbs or ends of the brackets E are connected the screw-threaded rods H, with whose inner ends engage the threaded buckle J.

The lower ends of the brackets D overlap the upper ends of the section B, and have

openings therein, through which freely pass the stirrups K, the latter having their legs firmly secured to said section B, the inner portions of said stirrups being extended so as to receive the wedges L which are adapted to ride upon the adjacent portions of the brackets D and thus firmly connect the sections A and B as one, it being noticed that said sections are formed of strong but sufficiently pliable metal that their ends may be drawn inwardly for purposes to be hereinafter explained.

The exterior section is divided at top where the inner ends of the divisions have brackets M secured thereto and rising therefrom, the same receiving the bolts N on which are nuts P whereby said divisions may be connected as one and provision is made for lateral adjustment of the divisions.

On the side portions of the divisions are shoulders Q against which may be seated the braces R which also engage the walls of the trench in which the sewer, conduit, etc. is formed.

The operation is as follows:

After the trench is formed, a mass of concrete, cement or other plastic material is placed on the bottom and sides of the same to form say the lower half of a sewer, conduit, etc. the extent of the material being in accordance with the thickness of the sewer, conduit, etc. to be formed.

The lower section B is now placed in the trench and rested upon said mass. The upper section A is then fitted on said lower section B and coupled therewith by means of the stirrups or butt straps K, the end portions of said upper section having been drawn in or contracted by operating the buckle G so that they will pass over said stirrups, after which said end portions are expanded so that the brackets D bear against the lower section B, when the wedges L are introduced into the stirrups and forced into the same, thus connecting said brackets with the lower sections and firmly uniting the two sections as one, as a complete inner mold, and the upper and lower sections may be coupled together at one operation and the material deposited in a monolithic form if so desired.

Another mass of the material is now placed on the upper portion of said mold as a continuity of the lower portion, thus forming the contour of a sewer, conduit, etc., endless 5 in circumferential direction.

The upper exterior section C is duly set up and material admitted at the top to the required thickness of the conduit, etc. For the operation of said section C, I employ 10 chains S which are passed around the rods N and the plank T which is placed across the trench, thus providing convenient means of directing said section C into position.

The braces R are also located and forced 15 downwardly, whereby as they press against the shoulders Q, the section C causes a compression of the mass of material from above and imparts the desired shape to the exterior of the sewer, conduit, etc.

20 The buckles G, J, are now operated so as to compress the mass from within, thus molding and centering the interior of the mass which, when set, produces a properly-shaped, uniform, strong and durable and comparatively 25 inexpensive mold.

The upper section C may then be released, raised and thereby removed at the top of 30 the trench and the sections A, B may be contracted and disconnected and each section withdrawn at the open end of the sewer, conduit, etc.

The upper end of the trench may be filled in, thus covering the top of the sewer, conduit, etc.

35 In order to provide a strong connection for the rods F and H with the respective brackets D, E, said rods have their ends bifurcated as at U and have passed through them the bolts V which bolts, when tightened by 40 suitable nuts, firmly connect the rods and brackets, the effect of which is evident.

45 It is evident that the upper and lower sections A, B, may be coupled and lowered in position when the material may be introduced and passed entirely around the exterior of said sections in the trench and so produce at one operation a monolith conduit, etc., the same being homogeneous and seamless.

50 In order to reinforce the sections of the mold, I employ the braces W which are of the form of V-shaped or acute angle bars of suitable metal, the same being riveted or otherwise rigidly secured to the interior of the sections in the longitudinal direction thereof, thus stiffening and strengthening the same.

At the ends of the sections and between 60 the ends, there are L-shaped braces X, the same being riveted or otherwise rigidly secured to the interior of the sections and extending in the circular or transverse direction of the sections or at a right angle to the braces W, thus additionally strengthening 65 the mold.

In the braces X are the eyes F' with which the rods F are connected, the ends of which latter in the present instance being of the form of hooks F², which are received in said eyes, the same, however, acting similarly to the connection of said rods with the brackets D and serving the purpose of adjustment of the sections in their expansion and contraction as in the other figures.

70 Between the inner limbs of the braces W there are longitudinally-extending wedges Z, preferably of wood, the same being bolted, or otherwise firmly secured to said limbs.

75 After the sections have been expanded, said wedges are driven in between said limbs, after which the bolts, or other fastenings are applied, it being seen that said wedges form an abutment for said limbs and prevent closing of the sections at the joint, while with the assistance of the braces W, they strengthen 80 the joints of the sections which in the present case are at the top and bottom thereof.

Having thus described my invention, what I claim as new and desire to secure by Letters Patent, is:

90 1. In combination, a tubular mold comprising parti-tubular sections of flexible material, angle irons secured to the opposing edges of one section with one leg of each overlapping edge of the other section, rigid adjusting means extending transversely of the mold and secured to the free legs of the opposing angles whereby the edges may be sprung in and out, and means whereby the edges of the other section may be sprung in and out.

95 2. In combination, a tubular mold comprising parti-tubular sections of flexible material, flanged stiffening sections secured to the opposing edges of one section with one leg of each overlapping the edge of the other section, rigid adjusting means extending transversely of the mold and secured to the free flanges of the opposing sections whereby the edges may be sprung in and out, and means 100 whereby the edges of the other section may be sprung in and out.

105 3. In combination, a tubular mold comprising parti-tubular sections of flexible material, angle irons secured to the opposing edges of one section with one leg of each overlapping the edges of the other section, and rigid adjusting means extending transversely 110 of the mold and secured to the free legs of the opposing angles whereby the edges may be 115 sprung in and out.

120 4. In combination, an exterior mold member comprising opposing parti-tubular sections spaced apart at the top, and bolts connecting the two parts whereby they are 125 held securely in their relative positions and a space for the introduction of material is provided.

130 5. In combination, an exterior semi-cylindrical mold member comprising opposing

parti-tubular sections spaced apart at the top, and adjustable means connecting the two parts whereby they are held in their relative positions and a space for the introduction of material is provided.

6. In combination, an exterior mold section comprising a parti-tubular member, projecting blocks Q for steadyng the ends of side braces, and means whereby the mold section may be supported.

7. In combination, parti-tubular sections, acute securing angles at the opposing edges thereof, a stiffening wedge fitting therebetween and means for securing the wedge rigidly to the angles.

8. In combination, opposing parti-tubular members of flexible material, stiffening

flanged members extending circumferentially of the sections, and transverse adjustable means for engaging the flanged members adjacent the edges of the parti-tubular member.

9. In combination, opposing parti-tubular members of flexible material, stiffening sections having projecting legs extending circumferentially of the sections and provided with a plurality of engaging holes spaced therealong; and transverse securing struts adapted to engage removably the holes in opposing sections.
